John Alexander Hugh Cameron
Attorney.

UNITED STATES PATENT OFFICE.

JOSEPH ODILON REMILLARD, OF MONTREAL, QUEBEC, CANADA, ASSIGNOR OF ONE-THIRD TO ALPHONSUS GORMAN AND ONE-THIRD TO JOHN ALEXANDER HUGH CAMERON, BOTH OF MONTREAL, CANADA.

NONSPASH BOTTLE OPENER.

Application filed June 14, 1922. Serial No. 568,344.

To all whom it may concern:

Be it known that I, JOSEPH ODILON REMILLARD, a British subject and a citizen of the Dominion of Canada, residing at the 5 city of Montreal, in the Province of Quebec, Dominion of Canada, have invented a new and useful Nonsplash Bottle Opener, of which the following is a specification.

My invention relates to a bottle-opener 10 by which any thin stopper in a bottle, whether of wood, card-board, cork, rubber, paper, fibre or other substance or metal, may be partially or wholly removed from the neck of a bottle without the liquid contents 15 thereof being spilled or splashed in any way.

I attain these objects by a mechanism illustrated in the accompanying drawing in which—
20 Figure 1 is the front or top view of the non-splash bottle-opener, showing the long hollow removable sharp-pointed metal cap 4 5 6, with a shoulder at 4, capable of penetrating a thin stopper with moderate pressure, in position on a circular metal pin 1 2 3; one portion 2 3 pressed or drilled round so as to receive said sharp-pointed metal cap 4 5 6, the other portion 1 2 split down the centre and pressed on or fastened 25 to an oval, circular, rectangular or square handle made of metal, mica, celluloid, rubber, wood, fibre, paper or other substance, in one piece or layer, or in more than one piece or layer, with space on the front and 30 on the back of each piece or layer for advertising;

Figure 2 is a front or top view of the non-splash bottle-opener, showing the hollow removable sharp-pointed metal cap 4 5 6 suspended by a small waterproof cord, one 40 end of which cord is passed through a small hole at 5 and knotted at the inner end at 5 and inside of the circular hollow opening 4 5 in said metal cap, the other end of 45 which cord is fastened at 7 by passing same through a small hole in the handle and securing this end by means of a knot; and

Figure 3 is a front or top view of the non-

splash bottle-opener, showing the neck of a bottle 8 9 with a stopper 10 11 in position, and said metal cap 4 5 6 removed from the metal pin 1 2 3 by the shoulder of the metal cap at 4 after penetrating the thin stopper 10 11, as soon as the metal pin 1 2 3 had been withdrawn from the thin stopper.

Similar numerals refer to similar parts throughout the several views.

Thus this non-splash bottle-opener will make it practically possible for a housewife or other person partially or wholly to remove any thin stopper from a bottle, without causing the liquid contents thereof to spill or splash in any way: (a) partially, if only a portion of the liquid contents 60 thereof is to be used, in which event the thin stopper may be placed back in position; and (b) wholly, if all of the liquid contents thereof is to be used.

I claim:

1. In a bottle disk remover, the combination of a pointed cap-like member having an open end, an aperture at the base of the opening, a handle comprising a pin adapted to seat in the cap opening and a finger hold attached to said pin, a flexible waterproof cord passing through the aperture at the base of the cap opening and connecting said cap with said pin member, all substantially as set forth.

2. In a bottle disk remover, the combination of a pointed cap-like member having an open end, an aperture at the base of the opening, a handle comprising a pin adapted to seat in the cap opening and a finger hold attached to said pin, a flexible waterproof cord passing through the aperture at the base of the cap opening and connecting said cap with said pin member, said finger hold being split down the centre to permit its being fastened to a flat handle, in one layer, or in more than one layer, with space available on the front and on the back of each layer for advertising, all substantially as set forth.

JOSEPH ODILON REMILLARD.
